UNITED STATES PATENT OFFICE

95,242

DESIGN FOR A SHINGLE ROOF

Herbert G. Goslin, Battle Creek, Mich., assignor to Sherriff-Goslin Roofing Company, Battle Creek, Mich.

Application February 9, 1935, Serial No. 55,325

Term of patent 7 years

To all whom it may concern:

Be it known that I, Herbert G. Goslin, a citizen of the United States, residing at Battle Creek, in the county of Calhoun and State of Michigan, have invented a new, original, and ornamental Design for a Shingle Roof, of which the following is a specification, reference being had to the accompanying drawing, forming part thereof.

The figure is a perspective view of a shingle roof, embodying my new design.

I claim:

The ornamental design for a shingle roof, as shown.

HERBERT G. GOSLIN.
